UNITED STATES PATENT OFFICE.

EDWIN YAWGER, OF PITTSBURG, PENNSYLVANIA, AND WILLIAM W. CHURCHILL, OF NEW YORK, N. Y., ASSIGNORS TO THE WESTINGHOUSE MACHINE COMPANY, OF PITTSBURG, PENNSYLVANIA, A CORPORATION OF PENNSYLVANIA.

FURNACE.

SPECIFICATION forming part of Letters Patent No. 746,908, dated December 15, 1903.

Application filed December 3, 1902, Serial No. 133,699. (No model.)

To all whom it may concern:

Be it known that we, EDWIN YAWGER, of Pittsburgh, Allegheny county, Pennsylvania, and WILLIAM W. CHURCHILL, of New York, 5 in the county of New York and State of New York, have invented certain new and useful Improvements in Furnaces; and we do hereby declare that the following is a full, clear, and exact description thereof, reference-being had to the accompanying drawings, and 10 to the letters of reference marked thereon, which form a part of this specification.

This invention relates to improvements in furnace-grates for mechanical stokers or devices for continuously feeding fuel to furnace-fires of that class embracing an inclined grate consisting of a plurality of transverse rocking grate-bars, which are arranged in stepped and overlapped relation—such, for instance, 15 as that shown in prior United States Letters Patent granted to William R. Roney on the 20th day of August, 1889, Nos. 409,304 and 409,305.

The invention relates more specifically to 25 improvements in the actuating devices for rocking or oscillating the bars of such inclined grates to facilitate the feeding of the fuel to the grate.

The invention consists in the matters hereinafter set forth, and more particularly pointed out in the appended claims.

In the drawings, Figure 1 is a central vertical longitudinal section of the front part of 30 a grate embodying the invention shown in said prior patents, showing also the actuating devices for the grate and our improvement embodied in said actuating devices. Fig. 2 is a section showing the outer end of 35 the connecting-rod by which the grate-bars are oscillated or rocked and associated parts, showing in section the parts constituting our invention. Fig. 3 is a cross-section on line 33 of Fig. 2. Fig. 4 is a face view of one of the nuts on the connecting-rod.

40 As shown in said drawings, A designates a part of the front wall of a furnace in connection with which our improvements are employed.

B designates an inclined grate consisting of a series of transversely-arranged grate-bars 50 B', which have stepped and overlapping relation, said grate-bars having bearing at their ends in side bearers C, one of which is shown in Fig. 1 of the drawings.

D designates a hopper located exterior to 55 the furnace and at the head of the inclined grate B and from which the fuel is fed to said grate, the fuel passing from said hopper to the grate over the usual dead-plate D'.

E designates an endwise-reciprocating actuating-bar arranged transversely to the grate-bars, with which each of the individual grate-bars B' is operatively connected and by means of which said grate-bars are rocked in 60 their bearings.

F designates a connecting-rod through which endwise-reciprocating motion is communicated to the actuating-bar E from agitating devices located exterior to the furnace-wall. The outer end of said connecting-rod 70 F is operatively connected with a continuously-rotating eccentric-shaft G, which is located transversely in front of the furnace-wall A and mounted horizontally in bearings A', fixed to said front wall of the furnace. 75 The connections between said crank-shaft G and the connecting-rod F are made as follows:

G' designates an eccentric-ring mounted on 80 said shaft, and G² an eccentric-rod, the strap g of which encircles the eccentric and the outer or free end of which rod is pivotally connected with the lower end of an agitator lever or arm H, which latter is affixed at its upper end to a rock-shaft I, mounted in depending brackets D² on the wall of the hopper. The lower end of said arm or lever H is provided with a rectangular loop h, which 85 encircles the outer end of the connecting-rod F. Within said loop is located a tappet-block H', which is provided with oppositely-extending trunnions h', engaging bearing-apertures in the parallel sides of the loop h, these parts being like the corresponding parts shown in the prior United States Letters Patent to Roney *et al.*, No. 586,976, granted July 27, 1897. 90

Referring now to the features of construction in which is embodied the present invention, said parts are made as follows: The forward end of the connecting-rod F, which passes through the tappet-block H', is provided at the inner and outer sides of the said block with adjusting-nuts f'f, which serve as tappet-shoulders for contact with the end faces of the block H' and which block when the lever or arm H is oscillated is adapted to act on said shoulders to impart to the connecting-rod and grate-actuating bar an intermittent reciprocatory motion. The connecting-rod F is screw-threaded at its outer end to receive both of the nuts f'f and to enable the said nuts to be moved or shifted endwise on the rod. Such shifting of the nuts is required in order to permit the extent of oscillatory movement, as well as the position of the grate-bars at one or both limits of such movement, to be changed, as required, in the use of fuel of varying qualities. In order to prevent contact of the tappet-block H' with the screw-threaded part of the rod F, a tube f² is interposed between the nuts f'f, the exterior cylindric surface of said tube constituting a bearing for said tappet-block H'. The tube f² is attached to or made integral with one of the nuts f, said tube being herein shown as screw-threaded at one end and entering a counter-bored recess in the adjacent end of the nut f. The other end of the tube reaches to a point adjacent to the nut f', but is made not longer than the distance between said nuts when they are at a minimum distance apart.

f³ designates a jam-nut which has screw-threaded engagement with the said rod and is located in a concentric recess f⁴ in the outer end of the nut f. The recess f⁴ in the nut f is made of sufficient depth to entirely receive the jam-nut f³, whereby when the parts have been adjusted on the rod said jam-nut cannot be moved on the rod without first moving the nuts f'f and interposed tube away from the same. The outer nut f is made exteriorly cylindric, whereby a pipe or like special wrench is required to turn the same on the rod, while the inner nut f³ is provided with an angular perimeter, whereby it may be turned by the use of an ordinary wrench. The rod may be provided outside said jam-nut with a through-opening to receive a cotter-pin f⁵, which extends at its ends beyond the rod and prevents detachment of the nuts and tube from the rod.

In assembling the parts and adjusting the same on the rod the nut f' is first threaded on the rod, after which the tube f² and nut f are placed in position. Thereafter the jam-nut is threaded upon the rod and properly located, and the nut f backed outwardly on the rod and tightened against the jam-nut. When the cotter-pin is used, the hole therefor will be located in position to hold the pin in contact with the jam-nut. Instead of using said cotter-pin the thread outside the jam-nut may be spread or mutilated by a cen-

ter punch, so as to prevent the nuts from being moved outwardly on the rod. The nut f' will be adjusted at a suitable distance from the nut f, according to the extent of rocking movement desired in the grate-bars. Said nut will not be in contact with the sleeve f² except when the parts are adjusted to give a minimum extent of movement to the grate-bars. When it is desired to readjust the parts on the rod, the nut f' is first run back on the rod, after which the nut f and sleeve are moved inwardly away from the jam-nut f³. The jam-nut may then be turned to the position which it is to occupy in the newly-adjusted position and the nut f turned backwardly tightly against the same, carrying therewith the attached tube. Thereafter the nut f' is turned outwardly into position required for giving the desired movement to the grate-bars. When the parts are adjusted in the manner described, the adjustment of the nut f cannot be changed by the initial movement of either the said nut f or jam-nut f³ with the use of an ordinary wrench or implement at hand in an engine-room, because of the fact, on the one hand, that the nut f is exteriorly cylindric and requires a special wrench to turn it, and, on the other hand, that the jam-nut is entirely contained in the recess of said nut f' and is not accessible. To effect such readjustment, therefore, it is necessary to first release the nut f by means of a pipe-wrench or the like, and after shifting said nut away from the jam-nut to then place the latter in the desired position. The nut f' is intended to be turned freely by means of an ordinary wrench or by hand. To prevent said nut from being jarred out of place or from turning on the rod through the jarring of the parts, said nut is made of irregular shape, or, in other words, is weighted at one side of its center, as clearly seen in the drawing Fig. 4.

The advantage of the construction herein shown as compared with the construction of the similar parts illustrated in the aforesaid prior patent, No. 409,805, will be understood from the following: In the prior construction the nut at the outer end of the rod was so made as to be readily turned by an ordinary wrench found in every engine-room, and it has been observed from practical experience that readjustment of the parts are often attempted by attendants not authorized to do such work and who are ignorant of the requirements of such adjustment, in view of the character of the fuel being used. Such unauthorized tampering with the parts of the grate-actuating devices causes an uneconomical consumption of fuel and derangement of the fuel-feeding devices, which frequently requires the attention of an expert from the builders of the grate, not so much to properly adjust the devices as to discover that such adjustment is required. In the present construction, however, any harmful tampering with the adjusting devices is not likely

to occur, because of the inaccessibility of the nut f^3 , which must be moved before any adjustment of the nut f can be made.

It is to be noted that the position of the nut f determines the position of the grate-bars when their exposed edges, which support the fuel, are tipped downwardly and that the nut f' determines the position of the said exposed edges at the limit of their upward movement. It is undesirable that the bars should be even tipped too far upward, because this movement opens the spaces between the bars and would not only be liable to let the fuel through the said spaces, but by bringing the free edges of the bars into the burning fuel would thereby subject them to the liability of being burned or fused. By fixing the nut f to the rod so that it cannot be moved outward the downward movement or tilting of the bars may be limited so as to prevent them from being swung too far or brought into contact with each other, while by making the sleeve the proper length the nut f' is prevented from being moved so far out on the rod as to give undue upward movement to the bars. Movement of the nut f' inward on the rod or away from the sleeve merely lessens the upward movement of the bars, and as this adjustment of the nut can do no harm said nut is left free to be adjusted by an ordinary wrench or by hand. The operator is therefore free to adjust the movement of the grate-bars in a manner which cannot result in harm and which is the only adjustment required in the ordinary use of the device, while at the same time he cannot make any unusual, unnecessary, and harmful adjustment. The nut f is intended to be placed accurately in position when the parts are assembled by the maker, and said nut requires no adjustment except such as occasioned by wear. By the use of the cotter-pin f^5 or other expedient the jam-nut may be held from being moved outwardly under any circumstances, and this is desirable, inasmuch as the only adjustment ever needed for wear will be an inward adjustment required by reason of the stretching of the rod under the hammering action to which the nut f is subjected. If said nut f be adjusted inwardly to take up wear, it will be desirable to mutilate or swell the screw-threads outside of the jam-nut after adjustment, as by a center punch or hammer, so that the operator will

be prevented from moving the nut f and attached sleeve at all outwardly or in a direction which, by enabling the nut f' to be also moved farther out, would permit the exposed edges of the bars being thrown too far up and into the mass of fuel resting thereon. 60

We claim as our invention—

1. The combination with rocking grate-bars, and an apertured swinging agitator-lever, of a screw-threaded connecting-rod which passes through the aperture of the lever and provided on each side of the lever with a nut, a sleeve surrounding the rod between said nuts, the outer one of said nuts being exteriorly cylindric and provided with a concentric recess, and a jam-nut located in said recess. 70

2. The combination with rocking grate-bars and an apertured swinging agitator-lever, of connections between said bars and lever embracing a screw-threaded connecting-rod 75 which passes through the aperture of the lever and is provided on each side the lever with a nut, a sleeve surrounding the rod which is rigid with one of the nuts, the outer end of said nut being externally cylindric, 80 and provided with a counterbored recess, and a jam-nut located in said recess.

3. The combination with rocking grate-bars and an apertured swinging agitator-lever, of connections between said bars and lever embracing a screw-threaded connecting-rod which passes through the aperture of the lever and is provided on each side of said lever with a nut, a sleeve surrounding said rod between said nuts, the outermost of said nuts 90 being capable of turning on said rod and provided with means by which it may be locked thereon, and the innermost of said nuts being loose on the shaft and weighted at one side of its center to hold it from turning. 95

In testimony that we claim the foregoing as our invention we affix our signatures, in presence of two witnesses, this 16th day of January, A. D. 1901.
